UNITED STATES PATENT OFFICE

THOMAS L. SHERMAN, OF MELBOURNE, AUSTRALIA, ASSIGNOR TO MICHELL-CRANK-LESS ENGINES CORPORATION, OF NEW YORK, N. Y., A CORPORATION OF NEW YORK

CRANKLESS ENGINE

Application filed February 14, 1929. Serial No. 339,951.

This invention relates to engines and particularly to engines of the crankless type, such as that disclosed in Michell Patent No. 1,613,116.

- 5 In the patent referred to there is shown a crankless engine comprising a shaft on which are mounted two slants or swash plates, each slant coacting with opposed pistons.
- 10 This invention has for its salient object to provide an engine of the character specified so constructed and arranged that the engine shaft and parts carried thereby can be withdrawn from the engine casing without disturbing or removing the cylinders, pistons, or other operative parts of the engine.

Further objects of the invention will appear from the following specification taken 20 in connection with the drawings, which form a part of this application, and in which

Fig. 1 is a longitudinal, horizontal section of an engine constructed in accordance with the invention, this view being taken substantially on line 1—1 of Fig. 2;

Fig. 2 is a transverse sectional elevation taken substantially on line 2—2 of Fig. 1;

Fig. 3 is a transverse sectional elevation taken substantially on line 3—3 of Fig. 1;

30 Fig. 4 is a vertical sectional elevation of the engine shown in Fig. 1, this view being taken substantially on line 4—4 of Fig. 1;

Fig. 5 is a sectional elevation similar to

Fig. 1 but partly broken away, showing a 35 slightly modified form of construction;

Fig. 6 is a view similar to Fig. 2 but showing the modified form of construction illustrated in Fig. 5; and

Fig. 7 is a view similar to Fig. 4 but partly broken away, showing a slightly modified 40 form of construction.

The invention briefly described consists of a crankless engine of the opposed piston type, in which the shaft and operative driving connections between the shaft and the pistons are so constructed and arranged that the shaft and parts carried thereby can be removed from the engine casing without disturbing or removing the other parts of the 45 engine.

In the form of the invention illustrated in Figs. 1 to 4 inclusive, there is shown a casing comprising a main casing section 10 having a central portion A and end portions B and C.

55 The central portion A of the casing section 10 has cylinders 11 and 12 formed therein and also has bearings 13 and 14 for the engine shaft 15. The shaft 15 extends through the sections B and C and bearings 20 and 21 at the ends of the sections B and C are provided for the shaft.

60 Each of the cylinders 11 and 12 has a pair of opposed pistons 22 and 23 mounted therein. Each piston has a rod 25 connected thereto, on which is mounted a yoke 26 having pivoted thereto slipper bearing elements 27 and 28 which coact with opposite sides of a slant 30 mounted on the shaft 15. The outer ends of the rods 25 are mounted in 65 bearings 31 formed at the outer ends of the casing sections B and C.

70 The engine construction above described is fully illustrated in Patent 1,613,116, above referred to, and the particular details of the 75 cylinder pistons and operative connections between the pistons and the shaft form no part of the present invention and need not be further described.

The shaft 15 rotates in the four bearings 13, 14, 20 and 21, and each of these bearings consists of a pair of bearing blocks 32 and 33.

75 If desired, the bearings 13 and 14 may be omitted and a central bearing 35, shown in dotted lines in Fig. 1, may be substituted therefor.

80 The central portion A of the engine casing is normally closed by a cover plate 36 and covers 37 and 38 are provided for the end portions B and C of the engine casing. Since each of the bearings is split and the sections A, B and C of the casing are open at the top, it will be evident that the shaft 15 and the slants 30 can be lifted vertically 85 from the engine without in any way disturbing or removing the other parts of the engine, such as the pistons, yokes, etc. As a matter of fact, recesses are provided in the 90 ends of the central portion A and end por-

tions B and C for receiving the bearings for the shaft 15, so that the bearings and shaft can be lifted bodily from the lower part of the engine casing.

5 The construction shown in Figs. 5, 6 and 7 is similar to that illustrated in Figs. 1 to 4 but differs therefrom in that the cylinders 40 and 41 are not formed integral with the central portion A of the engine casing but 10 are supported at their ends in transverse frame members 42 and 43. The lower portion 44 of the central portion A of the engine casing may be formed integral with the end portions B and C or may be made separate 15 and be connected thereto in any suitable manner. The shaft 15 and parts carried thereby can be removed from the casing construction shown in Figs. 5, 6 and 7 in the same manner as above described in connection 20 with the embodiment of the invention illustrated in Figs. 1 to 4 inclusive.

From the foregoing description it will be clear that by reason of the construction described, the engine shaft and parts carried thereby can be readily and quickly removed from the casing by removing the covers for the central and end portions of the casing and then lifting the engine shaft and bearings vertically from the casing.

30 Although certain specific embodiments of the invention have been particularly shown and described, it will be understood that the invention is capable of modification, and that changes in the construction and in the 35 arrangement of the various cooperating parts may be made without departing from the spirit or scope of the invention, as expressed in the following claims.

What I claim is:

40 1. An engine comprising a shaft, a plurality of cylinders arranged parallel to the shaft and having their axes and the axis of the shaft disposed in a single plane, a pair of opposed pistons in each cylinder, and operative 45 driving connections between said pistons and said shaft, said connections being unobstructed in a direction at right angles to said plane, said shaft, driving connections, cylinders and pistons being thus so constructed and arranged that the shaft and parts carried thereby can be removed from the casing without disturbing the cylinders or piston.

55 2. An engine comprising a casing having a plurality of vertically removable shaft bearings, a shaft mounted in said bearings, cylinders disposed parallel to the shaft, a swash plate on the shaft pistons in said cylinders, and operative driving connections between the swash plate and pistons, said connections including members carried by the pistons, slidably engaging the swash plate and so constructed and arranged that the 60 shaft and parts carried thereby can be re-

moved from the casing without obstruction and without disturbing the pistons.

3. An engine comprising a casing having a plurality of vertically removable shaft bearings, a shaft mounted in said bearings, 70 a swash plate on the shaft, a pair of cylinders disposed parallel to and on opposite sides of the shaft, pistons in said cylinders, and vertically unobstructed, slidable operative driving connections between the swash plate and pistons, said connections being so constructed and arranged that the shaft and parts carried thereby can be removed vertically from the casing without obstruction and without disturbing the pistons.

4. An engine comprising a casing comprising a section open at the top, vertically removable bearings carried by said sections, a shaft mounted in said bearings, a pair of cylinders in the casing and disposed on opposite sides of the shaft, opposed pistons in said cylinders, swash plates on said shaft, and operative connections between the pistons and swash plates, said connections being vertically unobstructed, whereby the swash plates and shaft can be vertically lifted from the engine casing without disturbing the pistons and connections thereof.

5. An engine comprising a casing having a removable section, bearings in said casing, 95 a shaft in said bearings, cylinders in said casing having their axes in a plane passing through the shaft axis, said bearings being removable in a direction at right angles to said plane, pistons in said cylinders, a swash plate on said shaft and connections between said swash plate and pistons, open to permit removal of the plate and shaft.
